SULPHONATED MINERAL OILS RICH IN SULPHUR CONTENT

Erich Arnold Wernicke, Hamburg, Germany, assignor to The Ichthyl Co., Rahway, N. J., a corporation of New Jersey

No Drawing. Original application January 9, 1934, Serial No. 705,918. Divided and this application August 13, 1937, Serial No. 158,915. In Germany January 11, 1933

8 Claims. (Cl. 260—504)

This is a division of U. S. Patent application Serial No. 705,918 filed January 9, 1934 (Patent No. 2,121,845, June 28, 1938).

The invention covered in the parent application, summarized herein, relates to a process for the production of sulphonation products of sulphur-bearing mineral oils, tar oils, and the like, containing two percent and more of organically combined native sulphur, and this division relates 10 to the new and improved products obtained by such processes.

Sulphonation products from mineral oils, tar oils, etc. have been used for many purposes, as for instance for the preparation of emulsions, for 15 general technical purposes, or for the manufacture of pharmaceutical preparations, for instance, products of the general type of sulphonated bitumen N. F. V. and the like, known under various proprietary names as "Ichthyl", etc. The products of this kind, obtained from sulphur-bearing oils, have a special importance in this respect.

Such sulphonation products as known to the prior art are of a very dark color and opaque, even in thin layers, because, in their production, the sulphuric acid employed in direct sulphonation exerts also a resinifying action due to oxidation or condensation effects, apart from the sulphonating action itself. The dark color of the sulphonation product is disadvantageous for many purposes and the strong odor is disagreeable. The presence of such side products necessarily also masks the effects of ultimate products in varying degree.

It is an object of the instant invention to produce water-soluble sulphonation products which shall be free from such objectionable properties without, at the same time, materially reducing the original native organic sulphur content of the oils to be treated. The prior art for mineral oil refinements for various special purposes was directed in the main to the most complete removal of the native sulphur. The object of the present invention is, on the contrary, to arrive at products which will be of light color, substantially transparent, and of rather pleasant odor or practically odorless, and yet to retain the native combined sulphur substantially unimpaired.

A noteworthy difference over the oil-refinement processes hitherto employed lies in the fact that the materials which are treated according to processes and objectives disclosed herein and in the parent application, cannot strictly be considered as hydrocarbon oils at all in view of their high sulphur content. For instance, a total sulphur content of 10% in such oils corresponds to a con-

tent of organically combined sulphur-compounds of approximately 50—60%, so that the refining experiences had with oils having less than 2% of sulphur, acid which may still be fairly classified as hydrocarbons, cannot simply be applied to the sulphur oils involved herein.

It must also be emphasized that usually the original color of the oils in question is not controlling. Thus, a naturally light-colored oil may, in the subsequent sulphonation, produce a dark 10 product containing considerable resinified material. It is, therefore, an object herein to remove, by the particular form of pre-treatment as more particularly illustrated in the parent application, all those oil substances which would 15 cause a dark coloration of the final sulphonation product, retaining, nevertheless, as much as possible the original sulphur compounds which are, for the purposes of the present invention, the most highly valuable constituents.

The present invention solves this task in such a manner that the oils or their distillates, or singular fractions, are freed, by preliminary separation before the sulphonation step, from those ingredients that might cause a dark coloration of 25 the end product in the sulphonation process, while still retaining the original sulphur compounds without substantial loss. With the original sulphur compounds thus retained, the oils are then carefully and gradually sulphonated under strong 30 cooling or with relatively dilute sulphuric acid, or with the use of a suitable inert diluent. In the sulphonation procedure several of the indicated processes may obviously be combined with each other.

The preliminary separation of the resinous and resinifiable materials, from the body of the oil put in process, can be carried out, for instance, with soda lye and with sulphuric acid. The permissible concentrations of the acid can be readily 40 determined from the character of the oil used. This should be such that on the one hand the resinifiable substances will be removed as far as possible and, on the other hand, that no material degree of sulphonation of sulphur compounds or 45 their removal will take place in the initial stages.

When the properties of a given crude sulphur-oil or distillate are unfamiliar, the appropriate strength of acid may be empirically ascertained by beginning with relatively low concentrations 50 and progressively increasing the strength in successive steps without effecting any appreciable sulphonation of the natural sulphur compounds of the oil until the unwanted components have been removed.

This separation can also be carried out with other agents which may be used either alone or combined, thus, for instance, with potash lye, aluminum chloride, phosphoric acid, fuller's earth, bleaching clay, and the like, depending on the chemical character of the oil.

That part of the oil, resulting from preceding sulphonations which cannot further be sulphonated may serve as a suitable diluent, in the ultimate carefully controlled sulphonation steps.

Depending upon the thoroughness with which the resinifiable material has been removed, and depending further upon the degree of care observed in the gradual and controlled sulphonation process, after neutralizing the sulphonation mixture and separating the undissolved portions of the oil, the applicant has been able to obtain a transparent, clear, water-soluble product of light-yellow to brown color, which does not materially impart its color to other substances when mixed with them, whereas without this treatment much darker, non-transparent products, usually having a strong, unpleasant odor, are obtained. The new products of the instant process are obtained more or less completely free from the strong unpleasant odors which are so characteristic of the products of the old art, such as bitumen sulphonatum N. F. V.

Following the first careful sulphonation, this can be repeated several times with sulfuric acid of graduated increase in strength, so that each sulphonation process can be regarded as a pre-treatment in the sense of the instant application for the sulphonation with the next-following stronger acid. The acid concentration to be employed in the successive sulphonation steps is downwardly limited by the acid concentration used in the preceding step; and by observing the necessary care in other respects, the concentrations may be increased up to the stage of fuming sulfuric acid. The greater the difference in concentration between two successive sulphonation steps, the higher is the sulphonation yield of the second step, but the more care and control will be required for the production of a sulphonation product of the desired physical and chemical attributes.

The following points broadly characterize the outstanding features of the present invention and its scope:

(1) Selection of oil high in native organically-combined sulphur content;

(2) Treatment to remove color-producing and other unwanted substances while nevertheless retaining major part of sulphur compounds before sulphonation;

(3) Reacting the oil containing the sulphur compounds with sulfuric acid to produce sulfonic acids containing not only the major part of the sulphur originally present, but also sulphur introduced by the sulfonating acid and obtaining said sulfonic acids as the desired product in a form free from objectionable color and odor. In both treatments the native sulphur compounds are retained; in the first they are not substantially affected and in the second treatment they are substantially converted into sulfonic acids, which latter serve in a sense as an intermediate for the production of the neutralized solution of the next step;

(4) This complex of clear, light-colored sulfonic acids of the preceding step, is then neutralized, preferably with ammonia, and produces then a clear aqueous solution, with all of the native sulphur substantially retained.

The end product obtained according to the present invention may be transformed to the desired consistency by adding water or by evaporation. The removal of excessive amounts of sulfates as may be desired, can be carried out in any well known manner, either before or after the neutralization, for instance by dialysis or by extraction with solvents.

According to this invention sulphur-bearing petroleum or other oils, for instance from Italian mineral coal, Middle-German brown coal, South-German bituminous shale, or similar combinations or mixtures may be used with equal advantage for the manufacture of such sulphonation products. Analogous deposits of coal-like materials which are equally suitable for the process according to this invention, on account of their sulphur content, are found in all parts of the world. Practically it is, of course, preferable to begin with the distillates because the refinement is thereby simplified.

Example I

As starting material a distilled Italian mineral coal-tar, having the following characteristics, is used: specific gravity of about 0.9 at 15°; sulphur content 8.8%; boiling points about 90-250°. 100 grams of this oil are pre-refined with a solution of caustic soda of 39° Bé., sulphuric acid of 70% H_2SO_4 and fuller's earth. The sulphur content after the pre-refinement is 10.22%.

The refined oil is now sulphonated with about 60 cc. sulphuric acid of 90% H_2SO_4 under stirring and cooling at 0° C. The sulphonation mixture is run into water, and sulpho-acid and oil are then neutralized with ammonia. After separating the oil, the product is evaporated to a water content of 41.24%. 10 grams are obtained of this product which, in this condition, contains 6.84% of ammonium sulphate and 9.57% of sulphur. The organic substance is 51.92% including 15.24% of sulphur. It has been calculated that the oil substance which has been sulphonated contains 11.01% of organic sulphur. The product is light brown, transparent and clearly water-soluble. The reaction products of the oil and sulphuric acid obtained in the end product are true sulpho-acids and not esters because the latter would be split by the strong heating which takes place in the dilution of the sulphonation product with water and in the evaporation of the water from the neutralized product.

Example II

As starting material a distilled Italian mineral coal-tar is used having the following characteristics: specific gravity of 0.890 at 15° C.; sulphur content 7.0%; boiling analysis:

	Per cent
101-200°	54.3
200-269°	95

531 grams of this oil are pre-refined with 35% solution of caustic soda, 85% phosphoric acid and fuller's earth. The sulphur content after the pre-refinement is 7.2%. The refined oil is now sulphonated with about 480 cc. of sulphuric acid (pure concentrated) under stirring and cooling at about -5° C., and sulpho-acid and oil are then neutralized with ammonia. After separating the oil, the product is then evaporated to a water content of 42%. 69 grams of this product are obtained. In this condition it contains 11% of ammonium sulphate and 10.62% of sulphur. The organic substance therein is 47%, including 16.92% of sulphur. It has been calculated that 75

the oil substance which has been sulphonated contains 10.38% of organic sulphur. The product is light-brown, transparent and clearly water-soluble.

Example III

As starting material a distilled Mid-German brown coal-gas-light oil is used having the following characteristics: specific gravity of 0.850 at 15° C.; sulphur content 6.0%; boiling analysis:

	Per cent
80 to 100°	2.5
100 to 150°	35
150 to 200°	92

500 grams of this oil are pre-refined with 50% solution of caustic potash and 50% sulphuric acid. The sulphur content of the oil after this pre-refinement still is 5.6%. The refined oil is now sulphonated with about 55 cc. sulphuric acid (pure concentrated) under stirring and cooling at about 0° C. The sulphonation mixture is run into water and neutralized with ammonia. After removal of the unaffected part of the oil, having become separated by the dilution with water, the product is evaporated to a water content of 30%. 50 grams of this product are obtained. It contains in this condition 8.67% of ammonium sulphate and 10.90% of sulphur. It has been calculated that the sulphonated oil substance contains 8.69% of organic sulphur. The product is light-brown, transparent and clearly water-soluble.

Example IV

As starting material a distilled Tyrolean shale oil is used having the following characteristics: specific gravity of 0.885 at 15° C.; sulphur content 11.3%; boiling analysis:

	Per cent
80 to 100°	1.8
100 to 200°	61.0
200 to 300°	94.1

524 grams of this oil are pre-refined with water-free aluminum chloride, 35% solution of caustic soda and fuller's earth. The sulphur content of the oil after this pre-refinement is still 11%. The refined oil is now sulphonated with about 425 cc. sulphuric acid (pure concentrated) under stirring and cooling at about -5° C. The sulphonation mixture is run into water and sulpho-acid and oil are neutralized with ammonia. After removal of the unaffected part of the oil, having become separated by the dilution with water, the product is evaporated to a water content of 30.5%. 105 grams of this product are obtained. It contains in this condition 4.77% of ammonium sulphate and 14.80% of sulphur. The organic substance therein is 64.73%, including 21.07% of sulphur. It has been calculated that the sulphonated oil substance contains 17.53% of organic sulphur. The product is light-brown, transparent and clearly water-soluble.

Example V

As starting material a distilled Tyrolean shale oil is used refined with 35% solution of caustic soda, 70% sulphuric acid, and fuller's earth, having the following characteristics: specific gravity of 0.894 at 15° C.; sulphur content 11.45%; boiling analysis:

	Per cent
130 to 200°	58
200 to 287°	96.5

7.15 kg. of this oil are sulphonated with 16 liters of sulphuric acid (technical 66° Bé.) under stir-

ring at a temperature of about -8° C. The sulphonation mixture is run into water and sulpho-acid and oil are neutralized with ammonia. After removal of the unaffected part, having become separated by the dilution with water, the product is evaporated to a water content of 24.25%. 1.84 kg. of this product are obtained. It contains in this condition 7.33% of ammonium sulphate and 14.87% of sulphur. The organic substance therein is 68.42%, including 19.13% of sulphur. The sulphonated oil substance contains 15.04% of organic sulphur. The product is light-brown, transparent and clearly water-soluble.

463 grams of the oil, separated by the dilution of the sulphonation mixture with water, having a specific gravity of 0.926 at 15° C., are diluted with an equal volume of petroleum and with 500 cc. of sulphuric acid (16 weight per cent of 66° Bé. technical acid + 84 weight per cent of technical 30 fuming acid with 18% of SO₃) under stirring at a temperature of about -15° C. The sulphonation mixture is run into water and sulpho-acid and oil are neutralized with ammonia. After removal of the unaffected part of the oil, having become separated by the dilution with water, the product is evaporated to a water content of 30%. 316 grams of this product are obtained which, in this condition, contains 10.95% of ammonium sulphate and 10.60% of sulphur. It has been calculated that the sulphonated oil substance contains about 12.8% of organic sulphur. The product is light-brown, transparent and clearly water-soluble.

Obviously, the various steps of the process 35 may be modified considerably with respect to the order and the number of steps and the specific materials used in the several methods exemplifying the pre-treatment and sulphonation steps, without departing from the spirit of the 40 invention substantially as described and claimed, and it is understood that I do not desire to limit myself to the specific embodiments shown in the foregoing examples, wherein numerous equivalent materials may be employed as noted. 45

I claim:

1. Sulphonated sulphur-bearing mineral oils which have their original sulphur content substantially unimpaired, being of a light yellow-brown color and clearly water-soluble.

2. Sulphonated sulphur-bearing mineral oils which have their original sulphur content substantially unimpaired, being of a light yellow-brown color and clearly water-soluble, and which will not impart their color to other substances 55 when mixed therewith.

3. Preparations comprising essentially aqueous solutions of sulphonation products of mineral oils, naturally rich in organically combined sulphur compounds, having their native sulphur content substantially unimpaired, being substantially neutral in reaction, transparent, of a light yellow-brown color, and clearly water-soluble.

4. Neutralized sulphonation products of mineral oil distillates, naturally rich in organically 65 combined sulphur compounds, having their native organic sulphur content substantially unimpaired, being transparent, of a light yellow-brown color, and clearly water-soluble.

5. Neutralized sulphonation products of mineral oil distillates, naturally rich in organically 70 combined sulphur compounds, having their native organic sulphur content substantially unimpaired, being transparent, of a light yellow-brown color, clearly water-soluble, and substan- 75

tially free from objectionable staining-color and odor.

6. An improved sulphur-rich sulphonate compound, comprising essentially the sulphonate reaction product of a sulphonating agent and a sulphur-rich distillate obtained from naturally sulphur-rich bituminous material, said distillate being substantially free from resinifiable and objectionable staining-color producing substances.

7. The physical and chemical reaction product resulting from the reaction between a sulphonating agent and a mineral-oil distillate, free from resinifiable and color-producing substances, such reaction product containing substantially unimpaired all of the organically combined sulphur compounds of the original native sulphur present in the distillate and the sulphur introduced by

the sulphonating agent, and being substantially of a clear, light brownish color, water-soluble, and free from objectionable odor and staining-color.

8. A neutralized physical and chemical reaction product resulting from the reaction between a sulphonating agent and a mineral-oil distillate, free from resinifiable and color-producing substances, such reaction product containing substantially unimpaired all of the organically combined sulphur compounds of the original native sulphur present in the distillate and the sulphur introduced by the sulphonating agent, and being substantially of a clear, light brownish color, water-soluble, and free from objectionable odor and staining-color.

ERICH ARNOLD WERNICKE.
